UNITED STATES PATENT OFFICE.

ISADORE LAWRENCE LESAVOY, OF NEW YORK, N. Y.

CHESS.

Application filed August 11, 1926. Serial No. 128,530.

This invention relates to the game of chess. I have found that this discouraging experience is in the great majority of cases immediately overcome when advantage is taken of the discovery that each of the different attacking or defending chess-men represents a definite, absolute function which I may designate the sacrifice-value. I have found that when two players of approximately the same amount of familiarity with the game of chess (such familiarity representing the sum, as to each player, of his study and experience), the one of the two players which wins a particular game is the one who happens to show the least amount of carelessness and forethought during that game; provided the two players are not widely different in intellectual power, and, above all, provided one of such players has not the advantage over the other which follows from a knowledge lacked by the other, of such sacrifice-values.

As is well known, the game-pieces or chess-men are of different types and capabilities of movement or maneuverability. The different types of chess-men comprise, in addition to the king, the pawn, the bishop, the knight, the castle and the queen. These six types of chess-men, only, are the ones employed, as the game has been played for centuries past; and the game as thus played, and as now being played, is the subject of the present invention.

To those skilled in the game of chess, the different permissible movements of the different chess-men are well known. Thus most people are probably aware that the piece attacked or defended is the king, while the other pieces enumerated are the attacking or defending pieces. To those who are not yet devotees of the game of chess, the different permissible movements of the attacking or defending pieces often seem so complicated and confusing, when first explained, that the game is considered too difficult to become acquainted with easily, and hence not worth the effort to attempt playing it, even though its recreational virtues are apparent and its value as a means of exercising the mental powers is generally admitted.

One of the objects of the present invention is to provide, in connection with an equipment of pieces representing a standard set of chess-men, significatory means giving easy and instantaneous, and preferably graphic, indication of the permissible movements of any particular chess-men.

Another object is to provide said means, and a means functioning as explained with the chess-men at rest on a board either at the beginning of a game or during the course of the game.

It is also known that many persons have attempted to take up the game of chess, and have even gone so far as to learn the permissible movements of different chess-men, and in some cases have even gone further and learned a good many of the standard and more common attacks and defenses, and yet have sooner or later dropped the game because of an apparently mysterious inability ever to win a game against certain

Another object of the invention is to provide, in connection with an equipment of pieces representing a standard set of chess-men, significatory means giving easy and instantaneous, and preferably graphic, indication of the comparative sacrifice-values or any two or more chess men.

Another object is to provide a means as last described and a means functioning with the chess-men at rest on a board either at the beginning of a game or during the course of the game.

One of the important objects of the invention is to provide a standard chess game, and yet one which may be used practicably as a teacher's assistant or chess-game-instructor.

The invention will be more clearly understood from the following description of an embodiment thereof as at present preferred; it being understood, of course, that such embodiment represents merely an illustrative one of the many possible ways of carrying out the invention. Therefore, as to the illustrative form of the invention shown in the accompanying drawings, it is particularly to be understood that the detailed description of such form now to be given is not to be taken as at all defining or limiting the invention itself. That is to say, the scope of protection contemplated is to be taken solely from the appended claims,

interpreted as broadly as is consistent with the prior art, and with explanatory references to the specification only where a claim is ambiguous or to be impliedly limited beyond its express terms to avoid such art in order to save the validity of said claim.

In the accompanying drawings:

Fig. 1 is a side elevation of one form of pawn according to the invention;

10 Fig. 2 is a substantially vertical section, taken on the line 2—2 of Fig. 1;

Fig. 3 is a side elevation of one form of bishop according to the invention;

15 Fig. 4 is a substantially vertical section, taken on the line 4—4 of Fig. 3;

Fig. 5 is a side elevation of one form of knight according to the invention;

20 Fig. 6 is a substantially vertical section, taken on the line 6—6 of Fig. 5;

Fig. 7 is a side elevation of one form of castle according to the invention;

Fig. 8 is a substantially vertical section, taken on the line 8—8 of Fig. 7;

25 Fig. 9 is a side elevation of one form of queen according to the invention;

Fig. 10 is a substantially vertical section, taken on the line 10—10 of Fig. 9;

30 Fig. 11 is a side elevation of one form of king according to the invention; and

35 Fig. 12 is a substantially vertical section, taken on the line 2—2 of Fig. 11.

It will be seen from the drawing, and particularly from the odd numbered views, that each of the chess-men incorporates a 35 shape or localized shaping similar to or suggestive of the familiar figure of the particular chess-man represented.

40 Thus, the pawn of Fig. 1 is of no particular configuration or other characteristic except that it is of smaller stature than the other pieces; the bishop of Fig. 3 at its top is provided with a bishop's mitre 14; the knight of Fig. 5 is provided at its top with a horse's head 15; the castle of Fig. 7 includes the conventional turret 16; the queen of Fig. 9 is provided at its top with a crown, 17; and the king of Fig. 11, of greater stature than the queen, is also provided at its top with a crown, 18.

45 50 It will further be noted that, as is usual with chess-pieces, the knight is of slightly less stature than the queen, and that the castle and the bishop, both of the same height, are of slightly less stature than the knight, yet taller than the pawn.

55 Referring now particularly to the even numbered views, these are fragmentary sections so laid out as to show the obverse faces of discs 19 secured to or integrally carried 60 by the different pieces, and to show such faces of said discs so that the faces will lie in planes perpendicular to the line of vision, as would be the case when a player is seated in back of his chess-men at a table on which 65 the chess board rests.

These discs 19, in the present case, carry graphic indications of the permissible movements of the pieces by which they are carried.

70 Thus the disc 19 for each pawn (Fig. 2) indicates plainly that the pawn may in any case be moved one square straight ahead, while, if the pawn can be moved so as to take an opponent's piece, the pawn may also be moved to a square either immediately to 75 the right or to the left of the square straight ahead. In this connection, note the criss-cross lines 20 indicating square boundaries, the junction point 21 of the butts of the arrows 22, such point indicating the assumed 80 location of the pawn on a square, and the length of the arrows as well as the "1" in the small circle, indicating the square to square travel of the piece on each movement thereof. Note, too, that the letter "T" is 85 opposite the heads of two of the arrows to indicate that these movements may be performed only when an opponent's piece can thereby be taken or captured.

90 Referring to the bishop's disc 19 of Fig. 4, we see again the criss-cross lines 20 and a circle 23 from which diverge various arrows 24. This circle carries within it the legend "Any No.". Note also that all these arrows are representative of diagonal travels across 95 the board. Thus the significance is that a bishop may be moved at any time any number of squares desired, and may be moved backward or forward, provided the line of travel is diagonally of the board.

100 Referring to the knight's disc 19 of Fig. 5, we see again the criss-cross lines 20, and the junction point 25 of various obtusely bent arrows 26; such arrows being arranged in pairs and each pair of arrows having a common staff 26a between their butts and the point on each arrow where a change of direction thereof establishes an obtuse angle as indicated. Such a graph as that just described, carried by the piece representing the 110 knight, easily and instantaneously points out to the tyro the permissible and only the permissible movements of the knight.

110 Referring to the castle's disc 19 of Fig. 8, we see again the criss-cross lines 20, and also the circle 23, from which diverge various 115 arrows 27. This circle carries within it the legend "Any No.". Note also that these arrows are representative of straight up and down and straight right and left travels 120 across the board. Thus the significance is that a castle may be moved at any one time any number of squares desired, and may be moved backward or forward, provided the line of travel is parallel to any one of the 125 lines 20.

130 Referring to the queen's disc 19 of Fig. 10, we see again the criss-cross lines 20, and the circle 23. From this circle diverge various arrows 28. Said circle, like the circle

- 23 of Fig. 8, carries within it the legend "Any No.". Note also that these arrows are representative of all the straight line travels permitted either to a bishop or a castle.
- 5 Thus the significance is that the queen may be moved at any one time any number of squares desired, backward or forward, and along either diagonal, or parallel to any one of the lines 20.
- 10 Referring to the king's disc 19 of Fig. 12, we see again the criss-cross lines 20, and the circle 23, and diverging arrows 28 as in Fig. 10. The circle here, however, carries within it the numeral "1". Thus the significance 15 is that the king may be moved at any one time in any direction the queen may be moved, but only one square.

I have hereinabove referred to the attacking and defending chess-men as having definite, absolute comparative sacrifice-values. Of course, in a certain situation, these values may vary somewhat; especially to the trained sense of a player of some experience. The safer rule, however, particularly for 25 one who is a beginner, is to assume that in all situations said values prevail. These values are as follows: Two pawns are worth one knight or one bishop; two bishops are worth one castle; two castles are equal in 30 value to the queen. That is, giving the pawn the arbitrary value of 1, the knight has the value of 2, the bishop the value of 2, the castle the value of 4, and the queen the value of 8.

35 See now the shapings of these five attacking and defending chess-men last referred to, as shown in Figs. 1, 3, 5, 7 and 9. The main body of the pawn of Fig. 1 is shaped like the Arabic numeral 1, the main body of the bishop of Fig. 3 and of the knight of Fig. 5 in each case is shaped like the numeral 2, the main body of the castle of Fig. 7 is shaped like the numeral 4, and the main body of the queen of Fig. 9 is shaped like the numeral 8.

In the present case, the king of Fig. 11 is shaped to reproduce the whole regal figure, and the monarch is shown as though fleeing, to indicate broadly the fact that the game is 50 won by attacking the opponent's king while protecting one's own.

Thus it will be seen that I have provided a standard chess-game, yet one well calculated to have all the advantages and attain 55 all the objects hereinabove set forth, one that may be constructed at comparatively small expense, one that may be engaged in for recreational as well as educational purposes by a beginner, and one that may be 60 played at for long periods without having a sense of unfamiliarity developed on subsequently playing the game with the usual type of chess-men as well as the usual type of chess board.

65 Inasmuch as many changes could be made they have dissimilar permissible movements 130

in the above constructions, and many apparently widely different embodiments of my invention could be made without departing from the scope thereof, it is intended that all matter contained in the above description or shown in the accompanying drawing shall be interpreted as illustrative and not in a limiting sense.

It is also to be understood that the language contained in the following claims is 75 intended to cover all the generic and specific features of the invention herein described and all statements of the scope of the invention which, as a matter of language, might be said to fall therebetween. 80

I claim:

1. A chess-man carrying visibly thereon, when the chess-man is located at a particular square on the chess board, an indicium suggestive of a permissible movement of said chess-man on said board. 85

2. A chess-man carrying visibly thereon, when the chess-man is located at a particular square on the chess board, a directional indicium graphically suggestive of a permissible movement of said chess-man on said board. 90

3. A set of chess-men including a plurality of chess-men of dissimilar type in that they have dissimilar permissible movements 95 relative to the squares of the chess board, each of said chess-men carrying an indicium suggestive of the permissible movements of that chess-man on said board.

4. A chess-man carrying visibly thereon, when the chess-man is located at a particular square on the chess board, an indicium suggestive of the sacrifice-value of said chess-man. 100

5. A chess-man carrying visibly thereon, when the chess-man is located at a particular square on the chess board, a numerical symbol suggestive of the sacrifice-value of said chess-man. 105

6. A set of chess-men including a plurality of chess-men of dissimilar type in that they have dissimilar permissible movements 110 relative to the squares of the chess board, each of said chess-men carrying a numerical symbol, different types of chess-man carrying different numerical symbols.

7. A set of chess-men including a plurality of chess-men of dissimilar type in that they have dissimilar permissible movements 120 relative to the squares of the chess board, each of said chess-men carrying a numerical symbol, a chess-man of one type carrying a certain numerical symbol, and a chess-man of another type carrying a numerical symbol 125 representing a multiple of the first mentioned symbol.

8. A set of chess-men including a plurality of chess-men of dissimilar type in that they have dissimilar permissible movements 130

relative to the squares of the chess board, each of said chess-men carrying a numerical symbol, a chess-man of one type carrying a certain numerical symbol, and a chess-man of another type carrying a numerical symbol representing a sub-multiple of the first mentioned symbol.

9. A chess-man shaped to suggest graph-

ically its familiar prototype and also shaped to suggest a numerical figure. 10

10. A chess-man carrying visibly thereon, when the chess-man is located at a particular square on a chess board, indicia suggesting a certain direction of movement and also suggesting a certain numerical value.

ISADORE LAWRENCE LESAVOY.
